UNITED STATES PATENT OFFICE.

WOLCOTT CLARKE WAGGAMAN, OF WASHINGTON, DISTRICT OF COLUMBIA.

DESIGN FOR A TRAFFIC-SIGNAL CASING.

Application filed September 14, 1927. Serial No. 23,406. Term of patent 3½ years.

To all whom it may concern:

Be it known that I, WOLCOTT CLARKE WAGGAMAN, a citizen of the United States, residing at Washington, in the District of Columbia, have invented a new, original, and ornamental Design for a Traffic-Signal Casing, of which the following is a specification, reference being had to the accompanying drawing, forming part thereof.

In the drawing:

Figure 1 is a side elevation of the traffic signal casing showing my new design and Fig. 2 is a cross section thereof.

I claim:

The ornamental design for a traffic signal casing as shown.

WOLCOTT CLARKE WAGGAMAN.
